DATA CONVERSION OPERATION
BOYERS, PA

Bill of Lading

The Subscripted refers to the true & honest Patent, and
making part of the same containing, a description
in the words of the said William Maguire him-
self of his improvement in the manufacture of paper
from straw, hay or other vegetable substances, for which
Petitioner Patent were granted to said William Maguire
to make on the 8th day of March 1828, and on
the 22nd day of May in the same year, which last
said Patent being hereby cancelled on account of de-
fective Specifications.

This improvement
or discovery consists in the use of hay and, its salts in
preparing straw, hay or other vegetable substances for the
manufacture of paper in the following manner viz:
To one hundred and twenty pounds of the straw or hay
take the hay procured from three or four bushels of straw,
or from fifteen or twenty pounds of the salts of hay
according to the quality, dilute it with a sufficiency
of water to boil the straw or hay which need not be
all immersed at the commencement as it will sink
during the process of boiling, boil the materials together
until the vegetable matter and knots become soft or
pulpy, or steep the materials in the solution sev-
eral days until the same effect is produced, drain
off the remaining liquid and rinse the materials
to cleanse them from any dirt or sediment; then grind
them in the usual way to be manufactured like
rags into paper. The petitioner claims as his exclusive
improvement in using every the use of the hay and
its salts and the mode of preparing the materials so
as to render them fit for the manufacture of paper.

Witness. (P. St. Spiddle)
